UNITED STATES PATENT OFFICE.

ADAM SOLLEN, OF NEW YORK, N. Y.

COMBINATION-GARMENT.

1,285,444.

Specification of Letters Patent. Patented Nov. 19, 1915.

Application filed September 18, 1913. Serial No. 254,581.

To all whom it may concern:

Be it known that I, ADAM SOLLEN, a citizen of Russia, residing at New York, in the county of New York and State of New York, have invented new and useful Improvements in Combination-Garments, of which the following is a specification.

This invention relates to combination garments and has particular application to a 10 suit of this character adapted to be worn, especially during cold and inclement weather, by workmen engaged in outdoor tasks, persons participating in outdoor sports and others desiring or requiring protection against severe climatic conditions.

As is well known, the usual overalls, sweaters, coats, trousers and the like, worn by mechanics and others working outdoors, and the winter sport suits used by hunters, 20 golfers, fishermen, and other sportsmen, afford but inadequate protection and warmth when the wearer is exposed to the rigorous, penetrating cold experienced from time to time throughout the winter season. In fact, 25 during exceedingly severe spells of winter weather it is often impossible for a person to work or to indulge in sport outdoors with any degree of physical comfort or safety, unless resort be had to the expedient 30 of wearing or wrapping up in several extra coats, sweaters, leggings, mufflers and other articles of apparel. Such a bundle of clothing is not only cumbersome, heavy and annoying, interfering with the free movement 35 and muscular activity of the wearer, but the contiguous or meeting portions of the separate garments and thelapping sections thereof form gaps or spaces through which the cold air passes, or percolates so that at 40 the best such extra clothing does not satisfactorily exclude the cold, and therefore gives but inadequate protection. It is the purpose of this invention to obviate all of the above objections recited as incident to 45 the character of clothing worn outdoors during rigorous weather, for I provide a combination garment which will not only give adequate protection to the wearer, but is of such light weight as to be worn with comfort and convenience, free from the heavy, 50 burdensome, dragging sensation which results from the wearing of several extra garments. Furthermore, one of the essential and exceedingly valuable features of my improved garment, and a factor which will ap-

peal forcibly to the workman or sportsman is that it is so cut and constructed that when worn it will permit all possible freedom of movement of the body and the limbs, irrespective of the position the person may assume in the performance of the task or occupation. For example, a mechanic working outdoors upon a particular job may have to stoop, bend, twist and turn in dozens of various positions in the performance of his task, and it is desirable and important that there be as little strain, pull or stress, or other interference of the clothing upon the muscles of the body and limbs, or in other words, that the muscular activity be untrammelled, because, as will be obvious, the pulling and binding of the clothing not only tires and decreases the efficiency of the person, but has a tendency to interfere with the accurate performance of the task.

With my suit no binding or pulling action is exercised, no matter what position the body or the limbs may occupy.

Another object of my invention is the provision of a combination suit, which, when worn, presents a neat, attractive appearance, and which when desired, may be washed and cleaned the same as any ordinary washable goods.

Furthermore, my combination garment is so constructed as to avoid overlapping parts or gaps through which the cold air may penetrate, and therefore the garment may be worn without other extra pieces of clothing, such as jackets, sweaters, leggings, or the like, this also tending to increase the comfort of the wearer by decreasing the weight of the clothing required.

I also aim to provide a combination garment which will embody the desired features of neatness, simplicity and utility, and which may be manufactured and marketed at a relatively low cost.

With the above recited objects and others of a similar nature in view, my invention consists in the construction, combination and arrangement of parts set forth in and falling within the scope of the appended claims.

In the accompanying drawings:

Figure 1 is a perspective view looking at the front of my improved suit as it appears when worn by a person.

Fig. 2 is a similar view looking at the rear.

Fig. 3 is a perspective view of the upper

portion or the coat section of the garment with a collar shown as elevated and in position to protect the neck and ears and lower portion of the face of the wearer.

5 Fig. 4 is a front view of the coat and waist section of the garment with the arms extended illustrating the looseness which gives the requisite freedom of movement to the arms of the wearer.

10 Fig. 5 is a perspective view of the trousers showing the position assumed to give freedom to the legs of the wearer when kneeling.

15 Fig. 6 is a plan view of one of the back sections of the coat prior to sewing.

Fig. 7 is a similar view of one of the front sections of the coat prior to sewing.

Fig. 8 is a plan view of a back section of the trousers.

20 Fig. 9 is a similar view of a front section of the trousers.

Fig. 10 is a perspective view of a portion of the quilted material from which the suit is made.

25 Fig. 11 is a cross sectional view through the quilted material.

Figs. 12 and 13 are perspective views of sections of the multiply quilted material, such as may be used in the manufacture of 30 the garment.

Fig. 14 is a vertical cross sectional view taken through the collar of the coat.

Fig. 15 is a view of the cuff portion of a trousers leg showing a modified form of 35 tightening or fastening means.

Referring now to the accompanying drawings in detail, the letter A indicates the coat and B designates the trousers of my improved combination suit. Both the coat and 40 trousers are formed throughout of multiply quilted material, such as is shown in Figs. 10 to 13, inclusive. The form of multiply quilt-stitched material which I prefer to employ is shown in Figs. 10 and 11 and is indicated, by the letter C. In this form the 45 material is made up of three plies of fabric, and includes an outer layer 1, of khaki, or other suitable cloth, which may be waterproofed or not, as desired, an intermediate layer 2 of suitable relatively soft and 50 flexible heat-retaining material, such as is felt, and an inner or lining layer 3, of lining cloth, such as canvas or the like, these three layers or plies of material being connected in 55 the piece by cross stitching *s*, such as is commonly known as quilt stitching. In the modified form of material shown in Fig. 12, in addition to the outer or khaki layer 1, the intermediate felt layer 2 and the lining 60 or canvas layer 3, I may also employ an additional layer 4 of paper, such as that commonly known as crinkled paper, this being preferably interposed between the outer or khaki piece 1 and the felt layer 2, and acts 65 as a heat-retaining layer, paper of course

possessing this well known characteristic. In case it is desired to make a very light weight suit, and to dispense with the more expensive felt layer 2, I may make the multiply piece of material as is shown in Fig. 70 13, by omitting the felt layer 2, and simply employing a paper layer 4' between the outer layer 1 and the lining layer 3; in every instance, however, as shown in said Figs. 10 to 13, inclusive, the quilt stitching *s* is 75 used. Whether I employ the quilt stitched multiply fabric shown in Fig. 10, or that shown in Figs. 12 and 13, such material may be made in the large piece or bolt, and when the suits are to be cut therefrom, a number 80 of the large pieces may be imposed one on the other to form a pile and a number of suits, or parts of suits cut therefrom in one operation by machines now well known for cutting piles of cloth. Thus a considerable 85 saving of expense and labor may be made in the manufacture of garments,

The coat A comprises two similar front sections 5 and two similar back sections 6. One of the cut but unstitched front sections 90 of the coat is shown in Fig. 7, and a similar back section of the coat is shown in Fig. 6. The vertical edges 7 and 8 of each front section 5 of the coat are cut straight and approximately parallel, and the vertical edges 95 9 and 10 of each back section are likewise so cut. Thus when a front and back coat section are joined by stitching the straight edge 8 of the front section to the straight edge 10 of the adjacent back section, there- 100 by forming the side seam of the coat, the straight edge 7 of the front section will lie at the front of the coat while the edge 9 of the back section will lie at the center of the back of the coat and is intended to 105 be united with the similar edge of the other back section, thereby forming the central back seam of the coat. The front and back sections of the coat are cut much longer and wider than is usually the case, and on 110 straight lines as above mentioned, so that when stitched together to form the complete coat, the armholes or sleeve openings 11 will lie beyond the shoulders of the person and well down toward the biceps, so that when 115 the sleeves 13 are fixed in the sleeve openings the sleeve seams 14 will lie below the shoulders and encircle the arms, as shown in Figs. 1 and 2. At the same time such an arrangement will give relatively long shoul- 120 der seams 15, thus allowing plenty of room for the play of the shoulders in the arms, and permitting the person to raise the arms, as will be understood by reference to Fig. 4, or to lower the same, as shown in Figs. 1 and 125 2, without any pulling, binding or drawing. The sleeves 13 are also of relatively great width and looseness, and somewhat of balloon formation, especially at the elbows, as indicated at 16, so that perfect freedom 130

of movement in the bending of the elbows and the swinging thereof may be attained. The sleeves taper toward the lower ends thereof and terminate in adjustable cuffs 17, 5 a plurality of buttons and buttonholes indicated at 18 being employed for tightening or loosening the cuffs, as in very cold weather it may be desirable to tighten the cuffs sufficiently around the wrist to avoid the entrance of cold air to the sleeves. The coat is provided with a storm collar 19, which is shown in cross section in Fig. 14, and comprises an outer section of 3-ply quilted material, such as is shown in Fig. 15, and indicated at 20 in said Fig. 14. The longitudinal edges of this section 20 are turned in, as shown at 21 and 22, the edge 21 being stitched to a single thickness of lining 23, as shown at 24, while the edge 22 of 20 the 3-ply material 20 is stitched through the neck band 25 of the coat and through the inturned edge 26 of the lining 23, so that when the coat collar is applied to the coat, there is no rough edge visible and a collar 25 of exceeding flexibility and neatness results. One front edge 27 of the collar overlaps the other front edge 28 to a considerable degree, as shown in Fig. 4, so that when the collar is turned up, as shown in Fig. 3, 30 the neck and lower portion of the face will be completely enveloped, and as the collar may be fastened by the adjustable neck band strap 29 and the storm strap 30, access of cold air through the laps of the collar will be prevented. The collar is made of such width and depth as to completely envelop the neck, ears, the lower portion of the face as well as the upper portion of the throat. The front of the coat may be closed 35 in any suitable manner, as by button and buttonhole arrangement. For this purpose a cloth strip 31, preferably of a single thickness, is stitched to one of the front edges of the coat and is provided with buttonholes 32 for receiving buttons 33 sewed to the other front section of the coat. The strip 31 is preferably made of a single thickness, because it gives a neater appearance and will not fray or wear as rapidly as if 40 it were made of the multiply quilted material. At the same time, as the front edges of the coat overlap, the buttonhole strip, which forms an edging strip, will prevent the entrance of cold air. To the bottom of 45 the coat is stitched a belt 34, adjustable at the front by means of a buckle and strap arrangement, shown at 35, so that the coat may be drawn snugly and tightly about the waist of the wearer. Inasmuch as the peculiar manner of cutting and stitching together the front and back sections of the coat will give to the body of the latter a full, loose bag-like effect, and as the belt of the coat is intended to fit the waist snugly, 50 the bottom section of said coat is tucked, 55 plaited or tacked during the stitching operation at suitable intervals, as shown at 36, so that when worn, the coat will present a loose, full, blouse-like appearance, as clearly understood by reference to Figs. 1 and 2. 70 The belt may be provided with buttonholes as shown at 37 for buttons 37' on the waistband 34' of the trousers of the garment as shown in Fig. 5. In this connection, I will state that in the manufacture of the garments, I prefer to make the belt of the coat of about the same size as the waist band of the trousers, with which it is to be worn, so as to obtain a snug, tight, fit, when the combination garment is complete. For example, if the trousers waistband is to be thirty-two inches, the belt of the coat is likewise made of substantially the same size. Instead of employing the buttonhole and button arrangement for securing the coat 80 and trousers together, any other suitable fastening means, such as ball and socket fasteners, hooks and eyes, and the like, may be employed. The trousers sections B are also made 90 throughout of the multiply quilted material, and each leg of the trousers comprises a front section 38 and a back section 39, stitched together on the outside seam 40 and the inside seam 41, the back sections being 95 united by the usual seat seam 42. The leg sections are cut from the multiply material so that when united they form trousers having a substantially snug waist line, and a wide, loose or baggy hip section b, the legs 100 ballooning or widening at the knee, as shown at b², and also at the calf, as shown at b³, and then tapering into relatively narrow cuff-like bottoms b⁴, which may be drawn tightly about the ankle through lacing 44 105 closing the slit 45, as shown in Figs. 1 and 2, or straps and buckles, as shown at 44^a in Fig. 15, or any other suitable fastening means may be employed. The purpose of the slits in the bottom or cuffs of the 110 trousers of course is to provide ample space, and the fastening means are loosened, to permit the insertion and passage of the feet, even when shoes are worn, the bottoms or cuffs being subsequently tightened to prevent the entrance of air, and also to allow 115 leggings to be worn, if desired and to avoid the use of unnecessary surplus material. By making the legs and seat sections of the trousers relatively wide and baggy, and by 120 so cutting the material as to form balloon-like sections at the calves, and which terminate in relatively narrow cuffs constituting the bottom of the trousers, I provide for permitting the free movement of the limbs, 125 in kneeling, stooping, bending and the like, as there is no section of the trousers to bind, pull or draw against the muscles. Each back section of the trousers is formed with a V-shaped cut as shown at 46, which when 130

closed by stitching, will give the necessary bulge or balloon effect of the calf section of the leg.

As heretofore stated, the belt is attached 5 to the bottom of the coat and the loose, or surplus material of such coat bottom is tucked or plaited into the belt so that a tight fitting effect is assured, and the belt acting to grip into the waist-line of the 10 wearer when the trousers are attached, keeps the entire garment in proper balanced relation and also prevents the admission of air at the waist-line.

While it is the purpose to connect the coat 15 and the trousers at the waist so as to constitute a single garment, yet at times if desired, one may be worn independently of the other and different coat sections may be worn with different trouser sections, or in 20 other words, interchangeable.

It will be noted that I have provided a combination garment, formed throughout of quilt stitched multiply material, and while the garment will present a neat fitting, at 25 tractive appearance, the garment is sealed or closed at all laps against penetration by cold. Furthermore, it will be seen that the garment is sufficiently loose fitting at essential places, such as at the shoulders, elbows, 30 trunk, hips, knees and calves, to permit ease and freedom of movement on the part of the wearer irrespective of what position he may assume, as it is impossible for the garment to bind at these points. On the other hand, 35 the garment fits tightly or snugly at points where the binding, pulling or drawing would not occur.

Such a garment will be found especially useful for outdoor workers, gunners, golfers 40 and others, as while providing the necessary warmth and comfort, it will not interfere with the agility or movements of the person, and being of comparatively light material, will not become burdensome when 45 worn.

While I have herein shown and described one particular embodiment of my invention, I wish it to be understood that I do not confine myself to all the precise details of construction herein set forth by way of illustration, as modification and variation may be made without departing from the spirit of the invention or exceeding the scope of the appended claims.

55 What I claim is:

1. A combination suit comprising a blouse-like coat section the body of which is composed substantially throughout of multiply quilt-stitched fabric, said coat section having balloon-like sleeves, and a trousers section composed substantially throughout of multiply quilt-stitched fabric and having balloon-like leg portions, said coat and trousers sections having sufficient fullness in 60 the body, sleeve and leg portions to permit 65

free and unrestricted movement of the body and limbs of the wearer, and means for connecting the sections together at approximately the waist-line of the wearer.

2. A combination garment comprising a 70 coat section and a trousers section and means for detachably uniting the two sections, both sections being composed substantially throughout of multiply quilt-stitched fabric, said coat section having a loose-fitting, 75 bag-like body portion including shoulder portions adapted to extend beyond the shoulders of the wearer and down to a point adjacent the biceps of the wearer's arms and also having balloon-like sleeves connected 80 with the shoulder portions and terminating in cuffs adapted to fit snugly about the wrists, said trousers section having relatively wide knee portions and loose-fitting 85 calf portions terminating in cuff sections adapted to be tightened to fit snugly about the ankles of the wearer.

3. In a combination garment, a coat section composed substantially throughout of multiply quilt-stitched fabric, said coat section having a relatively loose, bag-like body portion terminating in a belt member adapted when fastened to give the body portion a blouse-like contour, balloon-like sleeve members connected to the shoulders of the body 90 portion, said sleeve members terminating in relatively narrow cuffs, and a quilted storm collar attached to the neck-band of the body portion and having overlapping free edge 95 portions, and means for fastening such body 100 portions of the collar in overlapping position.

4. In a combination garment, a coat section composed substantially throughout of multiply quilt-stitched fabric and having 105 a loose-fitting, bag-like body portion provided with a belt adapted when fastened to give the body portion a blouse-like contour, the shoulders of the body portion being adapted to extend beyond the shoulders of 110 the wearer and down toward the biceps of the wearer's arms, loose, balloon-like sleeves fastened to the shoulders of the coat sections, and having relatively wide elbow portions, said sleeves terminating in relatively 115 narrow cuffs, and a storm collar also formed of quilted material connected with the neck-band of the coat, said storm collar having overlapping front edge portions and strap members for fastening such edge portions in 120 overlapping relation.

5. In a combination garment, a trousers section formed substantially throughout of quilted material and having wide leg sections formed with relatively wide, balloon-like knee portions and enlarged calf portions, said leg sections terminating in relatively narrow bottom portions adapted to fit snugly about the ankles of the wearer.

6. A combination cold-weather suit com- 130

- prising a blouse-like coat section the body of which is composed of multiply quilted fabric, said coat section having a contracted waist-band and balloon-like sleeves terminating in wrist-portions, and a trousers section composed of multiply quilted fabric and having a contracted waist-band and balloon-like leg portions terminating in ankle embracing ends, said coat 5 and trousers sections having sufficient fullness to permit free and unrestricted movement of the body and limbs of the wearer, and means associated with the respective 10 waist-bands of the two garment sections for 15 detachably connecting them together at approximately the waist-line of the wearer.
7. A combination garment comprising a coat formed of front sections and back sections, each section being cut to provide opposing vertical parallel edges of different 20 lengths, the longer edges of the back section being stitched together to form the back of the coat, with the shorter edges of the back sections stitched to the shorter edges of the 25 front sections to form the side seams of the coat, the longer vertical straight edges of the front section lying at the front opening of the coat, said coat section having relatively long shoulders extending beyond the 30 shoulders of the wearer, relatively loose sleeves for said coat having enlarged elbow portions and relatively narrow cuffs, a collar connected to the neck-band of the coat and having overlapping front edge
- portions, said collar when elevated being of sufficient width to completely envelop the neck of the wearer, a trousers section having leg members provided with relatively wide knee and calf portions and terminating in adjustable cuffs adapted to fit snugly 35 about the ankles of the wearer, a belt for the coat section adapted when fastened to give said coat section a blouse-like appearance, a waist-band for the trousers section adapted to fit snugly about the waist of the 40 wearer, and means for connecting the waist-band with the belt.
8. A body-enveloping garment made of quilted material secured adjustably about the neck, waist, wrists and ankles, fulled 45 between these body sections to allow freedom for universal body movement.
9. A body-enveloping garment including a blouse-like coat section and a trousers section each made of pattern sections of multiply quilted material including an outer 50 wearing fabric, an inner lining fabric and an intermediate felted layer all quilted together, said garment sections being provided with means whereby portions 55 thereof may be secured adjustably about the neck, waist, wrists and ankles of the wearer, and fulled between the body sections to allow unrestricted freedom for universal body 60 and limb movements.
- 65

In testimony whereof I have hereunto set my hand.

ADAM SOLLEN.
